UNITED STATES PATENT OFFICE.

EDMUND H. HANNON, OF DEDHAM, MASSACHUSETTS, ASSIGNOR TO THE STAFFORD COMPANY, OF READVILLE, MASSACHUSETTS, A CORPORATION OF MASSACHUSETTS.

LOOM PICKER-RETAINING DEVICE.

Application filed May 9, 1922. Serial No. 559,552.

To all whom it may concern:

Be it known that I, EDMUND H. HANNON, a citizen of the United States, residing at Dedham, in the county of Norfolk, State of Massachusetts, have invented a certain new and useful Improvement in Loom Picker-Retaining Devices, of which the following is a specification, reference being had therein to the accompanying drawings.

10 My invention has relation to devices of the class designed for retaining or assisting in retaining pickers in proper working position upon the picker-sticks of looms. It has for its object the provision of a positive, simple, and inexpensive device by means of which looseness and play of a picker of loop form relative to the picker-stick upon which it is mounted, the tearing loose of the picker from its customary securing screw, and the 15 working of the picker out of its proper place upon the picker-stick, shall be prevented.

20

The common type of loop picker which is illustrated in the accompanying drawings has been found to work loose upon the screw commonly employed for securing it in place upon a picker-stick, or even to tear away therefrom, under the severe pounding action to which it is subjected by the shuttle. This is due to the deflecting or tilting action of 25 the tip of the shuttle with which it cooperates, resulting from such tip striking one portion or another of the inclined sides of the conical hole which forms in the face of the picker, the said tip striking now high, 30 now low, or at the forward side or rearward side of the said depression and tending to twist the picker on its picker-stick in the corresponding direction. Also, the usual picker-securing screw sometimes works out, 35 permitting the picker to shift its position or be thrown off.

40 My invention comprises essentially a picker-retainer comprising a metal strip having at one end a bend flaring away from the picker-stick, and a reverse bend, the extremity adjacent such latter bend being arranged to take against the back of the picker-stick; preferably terminating at such extremity in a point or points adapted to be 45 driven into the picker-stick.

50 In the drawings,—

Fig. 1 is a view in vertical section of a 55 loop picker of common type in place upon a picker-stick and secured thereon by a

screw, and also by an illustrative embodiment of my invention.

Fig. 2 is a perspective view of said illustrative embodiment.

Having reference to the drawings,—

The picker 1 is a loop picker of common type and construction, comprising a plurality of layers 4 of leather and a filler-piece 2 which also may be of heavy leather. The loop of the picker adapts it, as usual, to encircle the picker-stick 3. A screw 5 is shown as driven through the plies 41 at the back of the loop, and into the picker-stick at the back thereof, such screw being a means usually employed in prior practice for retaining the picker in place.

70 The improved device which I provide for securing a loop picker in place upon a picker-stick, and for taking up looseness and play of the picker upon a picker-stick, comprises in its present embodiment a strip of metal 6 adapted to be driven in between the back of the picker-stick 3 and the adjacent inner surface of the loop of the picker, that is, in contact with the inner of the plies 41. The lower end of the device is formed with a chisel edge 61 to facilitate entering the strip between the picker-stick and the loop in applying it in the case of a tightly-fitting picker without injury to the picker-stick or 75 the loop of the picker.

80 I form the upper end of my picker-retaining device with a portion 62 which is bent at an inclination relative to the plane of the lower portion of the device, so that when the device is applied as in Fig. 1 85 at the back of a picker-stick such portion 62 flares away from the picker-stick. A terminal portion 63 adjoining said portion 62 is bent at an acute angle with the portion 62, so that it lies at right angles, or it 90 may be only approximately so, to the line of the main part of the device, and correspondingly to the rear face of the picker-stick. This portion 63 affords a face easily struck by a hammer in driving the picker-retainer down into position. This portion 95 63 is adapted to engage at its free extremity with the back of the picker-stick. Preferably, the said extremity is provided with one or more points 64 to enter the material 100 of the picker stick 3. In applying the device, after it has been driven down along the back of the picker-stick until it has

105

arrived at the desired position, fitting tightly in between the back of the picker-stick and the loop of the picker, a blow of the hammer against the outstanding angle 5 above the loop of the picker then serves to embed the point or points 64 in the wood, where they are held by the stiffness of the metal strip. This engagement of the point or points with the picker-stick prevents dis-
10 placement upwardly of the picker-retainer 6, while the outwardly bent portion 62 pre-
cludes the possibility of the picker rising upon the picker-stick. The entry of the outflaring inclined portion between the
15 picker-stick and the inside of the loop serves as described to wedge the loop firmly upon the picker-stick.

In the present embodiment of my invention, I have shown the picker-retainer pro-
20 vided with a hole 65 through which the picker-retaining screw 5 passes to reach the wood. As this screw often works out of the wood, as stated hereinbefore, especially so after it has been turned out and replaced
25 a few times in renewing the picker, I con-
template in some instances a provision for further security in the form of a screw-
thread in the hole 65 to engage the thread
of screw 5 and serve somewhat as a locknut
30 to prevent its working loose.

Since my picker-retaining device acts in-
dependently of the picker-retaining screw
5 and is adequate to hold the picker on, I
may in some cases dispense with the said
35 screw 5 or equivalent means, using my de-
vice alone to retain the picker.

What I claim is:—

1. The combination with a picker-stick, a loop picker mounted thereon, and a picker-
40 securing screw, of a picker-retainer com-
prising a metal strip interposed between the
said picker-stick and picker, having at its
upper end a bend flaring away from the
45 picker-stick, and a reverse bend, terminat-
ing in a point or points adapted to be forced
into engagement with the picker-stick.
2. The combination with a picker-stick,

a loop picker mounted thereon, and a picker-
securing screw, of a picker-retainer com-
prising a metal strip having at one end a 50
bend flaring away from the picker-stick,
and a reverse bend terminating in a point
or points adapted to be driven into the
picker-stick, and a hole to accommodate the
picker-securing screw. 55

3. The combination with a picker-stick, a
loop picker mounted thereon, and a picker-
securing screw, of a picker-retainer com-
prising a metal strip having at one end a 60
bend flaring away from the picker-stick,
and a reverse bend terminating in a point
or points adapted to be driven into the
picker-stick, and a hole provided with a
screw-thread to engage with the said picker-
retaining screw. 65

4. The combination with a picker-stick,
a loop picker mounted thereon, and a picker-
securing screw, of a picker-retainer com-
prising a metal strip having at one end a 70
bend flaring away from the picker-stick, and
a reverse bend, terminating in a point or
points adapted to be driven into the picker-
stick.

5. The combination with a picker-stick,
and a loop picker mounted thereon, of a 75
picker-retainer comprising a metal strip
having at one end a bend flaring away from
the picker-stick, and a reverse bend, terminat-
ing in a point or points adapted to be
driven into the picker-stick. 80

6. The combination with a picker-stick,
and a loop picker mounted thereon, of a 85
picker-retainer comprising a metal strip
having at one end a bend flaring away from
the picker-stick, and a reverse bend, terminat-
ing in an end which takes against the
back of the picker-stick.

In testimony whereof I affix my signature in presence of two witnesses.

EDMUND HANNON.
